UNITED STATES PATENT OFFICE.

CASPER FAUST, OF OSHKOSH, WISCONSIN, ASSIGNOR OF ONE-EIGHTH TO HERBERT NOLTE, OF ST. PAUL, MINNESOTA, ONE-EIGHTH TO JEREMIAH B. PUSHEE, OF MILWAUKEE, WISCONSIN, AND ONE-EIGHTH TO FRANK J. STOPPER, ONE-EIGHTH TO WALTER H. FAUST, AND ONE-EIGHTH TO FRANCIS J. FAUST, OF OSHKOSH, WISCONSIN.

TOY WAGON.

1,383,457.

Specification of Letters Patent. Patented July 5, 1921.

Application filed July 15, 1919. Serial No. 310,999.

To all whom it may concern:

Be it known that I, CASPER FAUST, a citizen of the United States, and resident of Oshkosh, in the county of Winnebago and 5 State of Wisconsin, have invented certain new and useful Improvements in Toy Wagons; and I do hereby declare that the following is a full, clear, and exact description thereof.

10 My invention relates to new and useful improvements in toy vehicles, more particularly of the wagon type and comprising a body supported by a rear wheeled axle and by a pivoted front wheeled axle. 15 It is in general the object of my invention to simplify the structure of devices of this character whereby to conduce to a maximum economy in manufacture and to increase the durability of such devices and the convenience of steering and other manipulations 20 thereof.

More particularly, it is an important object of my invention to provide a spring mounting for the body of a vehicle of this 25 character in a simple yet durable and efficient manner.

A further object resides in the provision of a simple brake mechanism for toy vehicles of this character, which mechanism is 30 operable to increase its braking operation upon tendency of rearward rotation of the vehicle wheels with which it is associated.

A still further object is to provide a draft handle for vehicles of this character which 35 may be readily operated by a person seated in the vehicle to procure steering movement, and to this end it is more particularly my object to provide a detachable fulcrum connection of the handle with the vehicle body.

40 A still further object resides in the provision of an improved wheel construction for toy vehicles of this character.

With the above and other objects and advantages in view, which will be apparent as 45 the description proceeds, my invention resides in the novel features of construction, combination and arrangement of parts, which will be hereinafter more particularly described and defined by the appended claim.

In the accompanying drawings:

Figure 1 is a side elevational view of a toy vehicle constructed in accordance with my invention, one rear wheel being removed and the front portion of the vehicle being broken away to more clearly show the novel 55 structure.

Fig. 2 is a bottom plan view of the vehicle, the rear axle being removed in this figure to show the brake structure.

Fig. 3 is a detail sectional view through 60 one of the wheels.

Referring now more particularly to the drawings, the body of the vehicle constituting the present exemplification of my invention comprises a slat bottom 5 on which is 65 secured the side walls 6 and front and rear end walls 7. A bolster 8 extends transversely under the forward end portion of the slat bottom and a central king-pin 9 is passed through the bottom and through 70 this bolster and through a front axle 10 carrying the wheels 11, the usual wear plates 12 being disposed between the axle and bolster.

The spring mounting for the body is pro- 75 cured in the present instance by a pair of spring rod lengths each bent intermediately to form a relatively large coil 13, the ends of each rod length being extended past the coil to form a relatively long body attach- 80 ing arm 14 and a short axle carrying arm 15.

Each of the arms 14 is secured at its extremitiy to an end portion of a strip 16 secured transversely under the rear portion of the vehicle body, and the arm extends rearwardly from the strip and seats in a trans- 85 verse groove of a spacer block 17 also secured transversely under the rear portion of the vehicle body. The short arms 15 terminate in eyes 16 which are secured by bolts 90 17 on the end portions of a rear axle 18 which carries the ground wheels 19. An exceedingly simple, yet durable and effi- 95 cient spring structure is thus afforded for the body, and it is noted that when the body is unloaded, said body inclines slightly downward toward its forward end to provide for a substantially horizontal posi-

tion under normal load conditions on the springs.

To provide a brake mechanism for the rear wheels 18, a lever 20 extends through the forward portion of the slat bottom 5 and has its lower end pivoted on a strap bracket 21 secured to the rear lower portion of the front axle bolster 8. A link 22 is pivoted to this lever under the body, said link extending rearwardly to the transverse spacer block 17 and being connected by a common pivot bolt 23 with the lapped inner ends of a pair of brake levers 24. These levers are provided with longitudinal slots 25 in their intermediate portions which receive pivot screws 26 depending from the block 17. These levers carry brake blocks 27, preferably of rubber, at their outer ends, said blocks being secured to the levers by bolts 28 passed through the blocks and the downturned extremities of the levers, and the levers are normally inclined forwardly from their pivot connections. Thus, forward movement of the link 22 procured by rocking the upstanding handle lever 20, will procure engagement of the brake blocks 27 with the upper side portions of the wheels. It is noted that the blocks engage the wheels prior to movement of the central pivot bolt 23 past the dead center line of the pivot screws 26, and thus rearward rotation of the wheels tends to more firmly bind the brake blocks and increase the braking action.

Each of the wheels of the vehicle preferably comprises a circular body disk 29 provided with a suitable tire member 30 of rubber or other substance disposed in a peripheral groove of the disk, said disk being centrally apertured. The axles of the vehicle are provided with preferably tapered spindle ends 31, and to provide a hub structure for the wheels having a considerably wider bearing surface than the width of the wheel disk, a pair of tubular hub sections 32 are engaged in the central aperture of the wheel disk and are provided with mating bores to receive the spindle 31, these hub sections being increased in diameter at the sides of the wheel disk to strengthen them and to provide annular shoulders 33 engaging the sides of the wheel disk to provide additional glue surfaces whereby the hub sections may be most firmly and durably secured to the wheel disks. This hub structure is retained on the spindle by a screw 34 threaded therein and carrying a washer 35 of greater diameter than the outer end of the spindle, which engages the adjacent hub section.

From the foregoing description it will be observed that the specific spring arrangement, between the body and the rear axle 18, will permit said axle to float under varying load strain, and it will also be noted that what may be termed the face brake blocks 25 will engage the inner faces of the wheel disks

at points which will vary with respect to the axis of said wheels, when the toggle link connection of the brake mechanism causes end thrusts thereof. Hence the brake mechanism and spring hangers are functionally closely related, and depend upon each other. As for example, under light load conditions, it will not require much braking power to lock the wheels and the end thrust which would tend to spread the wheels is comparatively light, so that said spreading tendency at the periphery of the wheel is slight. On the other hand when a heavy load is locked by the brakes, the braking blocks are comparatively close to the axle, and hence when extra heavy strain is put upon the braking blocks the tendency to spread the wheels, due to the braking power, is applied near the axis of said wheels, and spreading strain is reduced to a minimum.

To provide for connection of a draft handle 36 with the front axle, a single length of spring wire has its central portion bent to form a handle seating yoke 37 and from the ends of this yoke the wire is bent inwardly thereof to form loops 38 receiving a pivot bolt 39 for the handle, the wire being then curved downwardly and rearwardly from this loop and extended to form divergent arms 40 having their rear ends passed through and thus secured to the front axle. The handle 36 may thus swing freely in a vertical plane, and the bight portion of the yoke 37 serves to support the handle from contact with the ground when said handle in swung downwardly and forwardly. To provide for readily steering the vehicle by a person seated therein, a plate 40' is secured to and extends forwardly and downwardly from the top of the front end wall 7 of the vehicle body, said plate being then directed rearwardly and secured to the lower portion of the front wall. This plate is provided with a slot 41 adapted to receive a pin 42 projecting from the inner portion of the handle 36, when the handle is swung rearwardly against the plate. A detachable fulcrum is thus provided for the handle, and by swinging the handle laterally on this fulcrum, the front axle will be also swung to effect ready steering of the vehicle. It is noted that this fulcrum for the handle is disposed forwardly of the pivot axis of the front axle. Thus, swinging movement of the handle on the fulcrum in either direction will procure flexure of the spring rod connection of the handle with the axle, which will return the axle to its normal position when the handle is released, thus always tending to direct the vehicle in a fairly straight path.

While I have shown and described a preferred embodiment of my invention, it will be appreciated that to meet differing conditions of use and manufacture, various

changes and modifications of structure may be employed, and various phases of my invention may be employed separately within the scope of the appended claims, without departing in any manner from the spirit of the invention.

What is claimed is:

In a toy vehicle having a body provided with a wheel carrying front axle and a 10 spring connected rear floating axle provided with disk wheels; the combination of brake blocks arranged to engage the inner faces

of the disk wheels at varying distances, between the periphery of the wheel and the axis thereof, and manually actuated toggle 15 link connections for the brake blocks and adapted to cause the latter to move longitudinally of the wheel axle against the inner faces of the disk wheels.

In testimony that I claim the foregoing I 20 have hereunto set my hand at Milwaukee, in the county of Milwaukee and State of Wisconsin.

CASPER FAUST.
